UNITED STATES PATENT OFFICE.

RUTH COLLINS BENDIXEN AND MAUD E. MORROW, OF NEW YORK, N. Y.

DESIGN FOR A CHAIR.

Application filed May 29, 1929. Serial No. 31,467. Term of patent 3½ years.

To all whom it may concern:

Be it known that we, RUTH COLLINS BENDIXEN and MAUD E. MORROW, both citizens of the United States and residents of New York city, in the county of New York and State of New York, have jointly invented a new, original, and ornamental Design for Chairs, of which the following is a specification.

The figure is a perspective view of a chair, showing our new design:—

We claim:

The ornamental design for a chair, as shown.

Signed at New York city in the county of New York and State of New York this 21st day of May, A. D. 1929.

RUTH COLLINS BENDIXEN.
MAUD E. MORROW.
